UNITED STATES PATENT OFFICE.

CHARLES F. ROYSTER, OF CATLIN, ILLINOIS.

CAR-DOOR HANGER.

1,361,547.

Specification of Letters Patent. Patented Dec. 7, 1920.

Application filed December 29, 1919. Serial No. 347,961.

To all whom it may concern:

Be it known that I, CHARLES F. ROYSTER, a citizen of the United States, residing at Catlin, in the county of Vermilion, State of Illinois, have invented certain new and useful Improvements in Car-Door Hangers; and I do hereby declare the following to be a full, clear, and exact description of the invention, such as will enable others skilled in the art to which it appertains to make and use the same.

This invention relates to new and useful improvements in doors and particularly to doors for box cars.

15 The principal object of the present invention is to provide a novel and improved hanger for the sliding door of a box car wherein the usual wheels and rollers are done away with.

20 Another object is to provide a novel and improved hanger by means of which the door can be slid laterally with respect to the doorway of the car, and can be swung outwardly and upwardly therefrom.

25 Other objects and advantages will be apparent from the following description when taken in connection with the accompanying drawing.

In the drawing:

30 Figure 1 is an elevation of a portion of a box car showing the invention applied thereto.

Fig. 2 is a vertical sectional view taken on the line 2—2 of Fig. 1, showing the door 35 swung outwardly.

Fig. 3 is an enlarged vertical sectional view taken on the line 3—3 of Fig. 1, through one of the fastening means at the bottom of the door.

40 Fig. 4 is an enlarged vertical sectional view taken on the line 4—4 of Fig. 1, through the track, showing one of the hangers in end elevation.

Fig. 5 is a front elevation of a portion 45 of the track, broken away to show one of the hangers.

Referring particularly to the accompanying drawing, 10 represents the track which is secured to the side of the car over the 50 doorway 11, and extending a suitable distance to one side thereof. This track is formed with a longitudinally extending T-shaped slot 12, transverse bolts 13 being disposed through the track and slot thereof, 55 at the opposite ends to prevent the hangers from being removed from the track.

The hangers consist of hinge members

each comprising an upper leaf 14 and a lower leaf 15. The lower leaf is secured to the upper portion of the door by the bolts 16. 60 The upper leaf has the pair of openings 17 formed therethrough, and in each opening is a transverse pin 18 which has its ends resting on the ledges 19 of the slot 12. It will be noted that the slot 12 is in the form of an inverted T whence the formation of the said shoulders or ledges. The portion of the upper leaf, above the pins, rides in the upper vertical portion of the slot. Disposed above the pins and having recesses in their lower 70 faces, as shown at 20, for the reception of the ends of the pins, are the blocks 21. These blocks slide in the side portions of the horizontal legs of the T-slot.

Secured to the side of the car, below the 75 doorway, are the outwardly extending, and vertically apertured lugs 22, for the reception of the locking pins 23, carried slidably in the brackets 24, on the outer face of the lower portion of the door. These pins are 80 attached to the door by means of the chains 25, to prevent the same being lost when lifted from the lugs and brackets.

In the center of the horizontal portion of the T-slot there is formed a slot 26 which extends the entire length of the track for the 85 slidable reception of the portion of the upper leaf of the hinge hanger below the pins 18.

What is claimed is:

In a car door and hanger the combination with a track having an inverted and longitudinally extending T-slot therein, the horizontal portion of the slot opening through the bottom of the track the entire length 95 thereof, of a pair of hinged leaves, one of said leaves being adapted for attachment to a door, the other leaf being disposed through the open bottom of the T-slot and extending into the vertical portion of said 100 slot, transverse pins rotatably disposed through the said other leaf within the horizontal portion of the T-slot, and blocks disposed in the slot and having recesses in the bottom faces receiving the ends of said pins 105 rotatably therein and movable longitudinally of the track with the hanger.

In testimony whereof, I affix my signature, in the presence of two witnesses.

CHARLES F. ROYSTER.

Witnesses:

GEO. COLLINS,
T. F. WUREL.
